(57) **CLAIM**

The ornamental design for a builder's measuring and marking tool, as shown and described.

DESCRIPTION

FIG. 1 is a perspective view of my new, original and ornamental design for a builder's measuring and marking tool, according to a first embodiment;

FIG. 2 is a front view of the embodiment shown in FIG. 1; FIG. 3 is a top view of the embodiment shown in FIGS. 1-2; FIG. 4 is a bottom view of the embodiment shown in FIGS. 1-3;

FIG. 5 is a rear view of the embodiment shown in FIGS. 1-4; FIG. 6 is a left side view of the embodiment shown in FIGS. 1-5;

FIG. 7 is a right side view of the embodiment shown in FIGS. 1-6;

FIG. 8 is a perspective view of my new, original and ornamental design for a builder's measuring and marking tool, according to a second embodiment;

FIG. 9 is a front view of the embodiment shown in FIG. 8; FIG. 10 is a top view of the embodiment shown in FIGS. 8-9;

FIG. 11 is a bottom view of the embodiment shown in FIGS. 8-10;

FIG. 12 is a rear view of the embodiment shown in FIGS. 8-11;

FIG. 13 is a left side view of the embodiment shown in FIGS. 8-12; and,

FIG. 14 is a right side view of the embodiment shown in FIGS. 8-13.
